UNITED STATES PATENT OFFICE.

ULYSSES S. SMITH, OF SACRAMENTO, CALIFORNIA.

AIR-BRAKE SYSTEM.

No. 883,918.

Specification of Letters Patent.

Patented April 7, 1908.

Application filed April 24, 1907. Serial No. 369,918.

To all whom it may concern:

Be it known that I, ULYSSES S. SMITH, a citizen of the United States, residing at Sacramento, in the county of Sacramento and State of California, have invented certain new and useful Improvements in Air-Brake Systems; and I do declare the following to be a full, clear, and exact description of the same, such as will enable others skilled in the art to which it appertains to make and use the same, reference being had to the accompanying drawings, and to the characters of reference marked thereon, which form a part of this specification.

This invention relates to improvements in air brakes and particularly to the train line mechanism thereof, my object being to produce an air braking system whereby there may be braked by one control a much larger string of cars than is now possible with the present air braking systems, such regulation being accomplished by means of an automatic reduction of air at an intermediate point in the train line and by an automatic recharging of the same. This important object and many minor ones I accomplish by means of an auxiliary system of cylinders secured to locomotives or cars whereby the air from the air reservoir of an intermediate engine in a long string of cars will be automatically controlled and used in braking the cars to the rear of the said intermediate engine. This automatic control and use is controlled by the reduction and recharging of air from the train line pipe on the train in front of said intermediate engine or car, the initial control being, of course, in the hands of the engineer in the forward engine of the train.

The exact detail of construction and method of operation of this system will fully appear by a perusal of the following specification and the claims appended thereto.

In the drawings similar characters of reference indicate corresponding parts in the several views.

Figure 1 is a longitudinal section of the complete system. Fig. 2 is a vertical section of a rotary valve. Fig. 3 is a plan view of the under face of a rotary valve. Fig. 4 is a sectional view taken relatively on a line xx of Fig. 2. Fig. 5 is a top plan view of a graduating valve. Fig. 6 is an end elevation of an air cylinder. Fig. 7 is a plan view of the under face of a valve.

Referring more particularly to the refer-

ence numerals on the drawings 1 represents a cylinder connected at its front end by means of a pipe 2 to the exhaust port of the brake cylinder through triple valve on a locomotive tender or car. Arranged in said cylinder is a piston 3 having a rod 4 extending through the rear end thereof and slidably connected therewith is an arm 5 secured to a rotary valve 6 having a seat 7, the ports in said valve being arranged in a manner and for a purpose as will appear.

A port 8 leads from the valve seat 7 to the atmosphere. Another pipe 9 leads from said valve seat to the cylinder 1 for the purpose as will appear. A pipe 10 leads from said valve seat to the front end of a cylinder 11. Said cylinder 11 is connected with the rear of the cylinder 1 by means of a port 12, said port having a valve 13 in operative connection therewith within the cylinder 11. A rod 14 connects said valve 13 with a piston 15 disposed in said cylinder 11, the normal position of said piston being near the front of the cylinder 11 as shown in Fig. 1, said normal position being maintained by means of a spring 16, having four or five pounds compression.

A pipe 17 leads from the cylinder 11 to the rear of the normal position of the piston 15, thence through a valve 18 operated by hand and set for number of cars on train line by a spring clip handle 19 and provided with graduating ports 20, for the purpose as will appear. From said valve said pipe 17 leads to a tank 21 from whence a pipe 22 leads back to the cylinder 11 to the rear of a stop plate 15^a adapted to limit the backward movement of the piston 15 for the purpose as will appear.

A pipe 23 is adapted to connect the valve box 6^a of the valve 6 with the main air reservoir on a locomotive. Ports 24 lead from the valve seat 7 to a pipe 25 which enters an offset port 26 on a cylinder 27, said port 26 opening into said cylinder 27. Near the top of the port 26 is a cross head 28 having ports 29, and in the lower end of said port 27 is a similar cross head 30 having ports 31.

Disposed through the cross heads 28 and 30 is a rod 32 having secured thereto, intermediate said cross heads, a piston 33, the normal position of said piston being near the upper cross head 28, this normal position being maintained by means of train line pressure as will appear, and spring 34 encircling the rod 32 and bearing between the

top of the cross head 28 and a stop plate 35 on said rod 32, the tension of said spring will be strong enough to carry piston 33 to its normal position when rotary valve 6 has closed, as will appear.

In the piston 33 are small port holes 36, for the purpose as will appear in the *modus operandi* hereof.

37 is a pipe leading from the lower end of 10 the port 27 and adapted to be connected with the train line pipe on the train in front of the intermediate engine, in a train line, while a similar pipe 38 leads from the rear of the cylinder 27 and is adapted to be connected 15 with the train line pipe on the train to the rear of the intermediate engine.

Arranged in the cylinder 27 is a piston 39 having a rod 40 slidably mounted in the rear end of said cylinder, the normal position 20 being substantially as shown in Fig. 1, this normal position being maintained by means of a spring 41. A feed groove port 42 in the side of the cylinder 27 extends from the front to the rear of the said piston 39 when the 25 same is in its normal position. Ports 43 are also arranged in the sides of the cylinder 27 for the purpose of extending from the front to the rear of the piston 39 when the same is in its rear position in charging up of train 30 line, as will appear.

Leading from the cylinder 27 is an atmosphere port 44, a port 45 having a pipe 45^a leading to a train line governor, hereafter described, and a port 46 having a pipe 46^a leading to a throttle governor which is also described hereinafter. A valve 47 is connected with the rod 40 and operates over the ports 44—45 and 46, the connecting ports in said valve being described hereinafter.

40 The pipe 45^a leads to the rear of a cylinder 48, a pipe 49 connecting the front of said cylinder to the main air reservoir on the engine. Intermediate the entrance of the pipe 49 and pipe 45^a, a pipe 50 connects said cylinder 48 to said cylinder 27 to the rear of the point of the backward position of the piston 39.

Slidably mounted over the pipe 50 is a valve 51 having a port 52 adapted to coincide with the port 51 under certain conditions, but holding said port closed when piston 53 is in normal position, as will appear.

Disposed in the cylinder 48 intermediate the port 45^a and port 50 is a piston 53, the 55 same having a rod 54 secured to the valve 51 and having a spring 55 bearing between the rear of the piston 53 and the rear end of the cylinder 48, the purpose and tension of said spring being set forth in the *modus operandi* herein.

60 The pipe 46^a leads to the front end of a cylinder 56, there being a piston 57 disposed in said cylinder intermediate the entrance of said pipe 46^a and the rear of said cylinder, 65 said piston having a rod 58 leading to a lever

59 pivoted by a link 60 to the throttle lever 61, the lower end of said lever 59 having a link 62 extending therefrom around the escapement lever 63.

The *modus operandi* is as follows:—In using 70 my improved system every locomotive will be equipped with the parts just enumerated. When a train of cars is so long as to require one or more engines the pipe 2 on such intermediate engines is connected with the exhaust of the triple valve on either the tender or engine driving brake triple valve of said intermediate engine or on rear one of the forward cars. The pipe 37 is then connected to the main train line pipe of the forward string of cars, while the pipe 38 is connected to the train line pipe on the rear string of cars. For the purposes of this description I will elucidate this device, by way of example, say of one intermediate engine 75 with the forward string of cars amounting to about fifty, with a similar number to the rear. As a hypothesis from which to commence this description we will presume that both train line pipes, fore and rear, are charged with the regular engineers brake valve regulation seventy pounds pressure, the engineer's brake mechanism on the intermediate engine is cut off and the train pipe of the front section connected up with 80 pipe 37 while the pipe 38 is connected to the train line of the rear section while the method of automatically charging the rear train line will appear in the course of this description. The cylinder 27 being connected by pipes 37 and 38 also carries seventy 85 pounds pressure, both in front and rear of the piston 39, the port 42 keeping the same equalized. The engineer in the front engine 90 desires to set the brakes and for that purpose makes an initial reduction from the main train line say of ten pounds. By the time this reduction reaches the rear car of the front train line of fifty cars it usually amounts to about five pounds and thus, 95 through the pipe 37, reduces the pressure in the front of the piston 39, thus causing the pressure to the rear of said piston to drive it forward. This action slides the valve 47 along first opening the port 46 and permitting an air pressure to pass through the side 100 46^a to the cylinder 56, thus driving the piston 57 backward, which action pulls on the rod 58 which in turn pulls on the lever 59, thus causing the link 62 to release the escapement lever 63, whereupon the rod 58 pulls the throttle lever in such position as to close the throttle, thus shutting off the steam 105 automatically from said intermediate engine when the brakes are applied. The valve 47 then moves forward until a port 47^a opens to the atmosphere port 44 and I figure that the 110 five pounds reduction through the pipe 37 coupled with the frictional resistance of the piston 39 and its parts will permit of a ten 115 120 125 130

pound reduction from the rear train line through the port 44, thus making the rear train line reduction fully equal to that in the front train line.

When the reduction just described is accomplished and brakes set and engineer charges up and releases brakes, the exhaust from the brake cylinder through triple valve enters through the port 2 into the cylinder 1 forcing the piston 3 backward. This action causes the rod 4 to move the arm 5, thus rotating the valve 6, which action causes vents *a* in said valve to coincide with the ports 24. As this takes place a vent *b* in said valve connects the port 9 with the atmosphere port 8 thus relieving the pressure in cylinder 1 caused by back movement of the piston 3. When the vents *a* open to the ports 24 the ninety pound pressure of air from the main air reservoir through the pipe 23 passes through vents *a*, ports 24, pipe 25, ports 29 into cylinder 27, and as it does so forces the piston 33 downward to retard the air from passing through pipe 37. The air passing into the chamber 27 forces the piston 39 backward to its position intermediate the openings of the ports 43. Thus the air passes around through the said ports and recharges the rear train line pipe again even as the front main line is being filled from the front engine. When the rear train line pipe and cylinder 27 are charged to their normal pressure of seventy pounds the rotary valve is automatically closed in a manner as will appear, thus permitting spring 34 to carry piston 33 back to its normal position, thus opening pipe 37 into chamber 27 again.

The manner in which valve 6 is closed is as follows:—While the said rear train line pipe is being charged as just described a vent *c* in the valve 6 permits air to pass from the box 6^a into the pipe 10, thence into the cylinder 11, where it forces the piston 15 back against the stop plate 15^a, thus causing the rod 14 to slide the valve 13 over the port 12, thus closing it. The air then passes through the pipe 17, thence through one of the ports 20 in the valve 18 and into the storage tank 21. When the pressure in said pipe 22, tank 21 and main reservoir is equalized the pressure of said air combined with the spring 16 forces the piston 15 to its normal position as described, thus opening the port 12 and permitting the air to enter the cylinder 1 and force the piston 3 to its normal position as described and incidentally causing the valve 6 to rotate and close ports 24 and 10 and causing a vent *d* to connect the ports 8 and 9, thus permitting the air to bleed from tank 21 through cylinders 11 and 1 to the atmosphere. I figure that the time consumed by the air in passing through the pipe 10, cylinder 11, pipe 17, valve 18, tank 21, pipe 22, and again through cylinder 11 into cylinder 1, will be equal to the time required to

charge the train line pipe and then closing the ports 24 and 10 when said pipe line is charged as described. A more minute regulation is acquired in this respect, however, by means of the graduated ports 20, that size of port used being graduated according to the length of the train.

The rear train line pressure is maintained and governed in the following manner:—The tension of the spring 55 is equal to twenty 75 pounds pressure. The normal train line pressure is seventy pounds which is transmitted through the pipe 45^a to the rear of the piston 53, thus making the total pressure on the rear of said piston equal ninety pounds. 80 The pressure on the front of said piston is ninety pounds coming from the main air reservoir through pipe 49. Thus under ordinary circumstances the piston 53 is held at normal, thus causing the valve 51 to hold 85 port 50 closed as described. If for any reason the train line pressure reduces from its normal of seventy pounds, the pressure on rear of piston 53 reduces in the same proportion, thus causing the greater pressure in the 90 front of the said piston 53 to drive it backward, thus causing the port 52 to coincide with the port 50, thus permitting the ninety pounds air pressure from the main air reservoir to enter through pipe 49 and thence 95 through pipe 50 to cylinder 27, thus filling the deficiency. When the normal pressure of seventy pounds is restored the piston 53 returns to normal as described, thus closing the port 50.

When a reduction is made valve 47 travels ahead and causes port *e* to connect port 45 and atmosphere port 44 allowing all air back of piston 53 to escape to atmosphere, thus causing the ninety pounds pressure in front 105 of said piston to drive it as far rearward as possible thus blanking port 50, thus cutting off all pressure from main air reservoir. The object of this is to permit the controlling engineer to make several reductions without 110 permitting any main reservoir pressure to pass into train line during such reductions. Then when the pressure from the main air reservoir passes into cylinder 27 through valve 6 the excess pressure forces the valve 115 51 over port 50 and retains it there until the train line pressure is equalized, when said valve returns to its normal position ready to open up port 50 as soon as train line pressure gets below seventy pounds.

When the piston 39 returns to normal position after a reduction and recharge as described a vent *e* in the valve 47 connects the port 46 with atmosphere port 44, thus relieving the pressure from cylinder 56 and 125 thus leaving throttle lever free to be used as desired.

A pin 39^a is slidably mounted in the head of the cylinder 27 and is in alignment with the rod 40. A string 39^b bears between a 130.

collar 39^c and the head of cylinder 27, thus pin 39^a resists any over forward movement of piston 39 allowing too large a reduction. A sudden reduction of air from the forward train pipe causes piston 39 to be suddenly driven forward, striking pin 39^a compressing spring 39^b, sliding valve 47 past port 44, causing a sudden reduction from rear train pipe throwing brakes into emergency.

10 The reduction cylinder 27 is operative not only on locomotives, but can be placed on a car and connected to an intermediate point of a train line where only one engine is used. The object of this is to permit of the making 15 of a reduction in the middle of a long train line, thus permitting much quicker action in setting the brakes on the rear end and thus equalizing the braking power on the whole train line. In thus using cylinder 27 all the 20 other parts would be eliminated.

In case a storage reservoir was used in connection with the cylinder 27 in its position just described all the other parts would be used, except train line governor if said reservoir 25 was placed on the caboose. The mechanism would then be used to charge rear end of train line. This construction would be very beneficial on a long train or on the mountain grades where only one engine was 30 used.

I have provided in connection with the mechanism described herein a signal system in case of derangement of parts. A pipe 64 will connect port 8 with a signal whistle 65. 35 In case of derangement cylinder 27 and rotary valve 6 would be cut out and piston 3 would be forced back to its backward position and the air would escape through the whistle to atmosphere in releasing brakes, 40 notifying engineer on intermediate engine so that he could charge up the rear train pipe. When it was charged up he would throw his engineer's brake valve on lap position, which allows the head engineer to keep train pipe 45 charged and set the brakes.

Each section of my device will be provided with cut out cocks so that they could be cut out at any time desired.

Thus it will be seen that I have produced 50 an improvement in air brake systems whereby the braking power will be supplied for several hundred cars in several trains under one control, whereas under the present system very poor braking can be done on more than fifty cars.

While this description sets forth in minute detail the present construction and arrangement of parts of the device, still in practice many deviations from such detail may be 60 sorted to at will without departing from the spirit of my invention.

Having thus described my invention what I claim as new and useful and desire to secure by Letters Patent is:

65 1. In an air braking system a means on an

intermediate car of a train line for automatically reinforcing the train line pipe pressure, and an automatic means in conjunction therewith for governing the pressure to the rear thereof, as specified.

2. In an air braking system a means on an intermediate car for reinforcing the train line pressure, means for opening said first named means by the exhaust from brake cylinder through triple valve on said car, and means for automatically shutting off said first named means when the function thereof are performed, as specified.

3. In an air braking system auxiliary reduction cylinders connected to the train line pipe at intermediate points, and automatic recharging mechanisms in operative connection with said reduction cylinders and with the head engine, as set forth.

4. In an air braking system auxiliary recharging cylinders attached to the train line pipe at intermediate points thereof, and auxiliary reduction mechanisms in operative connection therewith and with the head engine, as specified.

5. In an air braking system rotary recharging valves connected to intermediate points of the train line pipe, means for conveying main reservoir pressure to said valves, and means for automatically opening and closing said valves, as specified.

6. In an air braking system rotary recharging valves connected to intermediate points of the train line pipe, means for conveying main reservoir pressure to said valves, means for automatically opening said valve with the exhaust from the brake cylinder through triple valves nearest said recharging valves, and means for automatically closing said valves when the train line is charged, as described.

7. In an air braking system charging valves connected to the train line pipe at intermediate points thereof, means for conveying main air reservoir pressure to said valves, means for automatically opening said valves with the exhaust pressure from the brake cylinder through triple valves nearest said first named valves, and means for automatically closing said valves with the main reservoir pressure, as specified.

8. In an air braking system a charging valve at an intermediate point in the train line pipe, means for conveying main reservoir air pressure thereto, means for automatically opening and closing said valve, a reduction cylinder connected to said valve and to the train line pipe, a train line governor in connection with said cylinder, and an automatic means in connection with said cylinder for closing the throttle valve of a locomotive when a reduction is taken in the train line, as and for the purpose set forth.

9. In an air brake system a cylinder connected to the exhaust port of a triple valve,

- a piston arranged in said cylinder, a rod secured to piston and extending through the rear of said cylinder, a rod slidably mounted on said first named rod and connected to a 5 rotary valve, means connecting said valve to the main air reservoir, and means connecting the train line pipe to said valve, as set forth.
10. In an air brake system a cylinder connected to the exhaust of a brake cylinder through a triple valve, a piston in said cylinder, a rod extending from said piston through the rear of said cylinder, a rod slidably connected to said first named rod and 15 to a rotary valve, a port leading from said valve to a cylinder beside said first named cylinder, a port leading from the rear of said last named cylinder to the rear of said first named cylinder, a piston in said last named cylinder having its normal position maintained near the front of said cylinder by a spring, a rod on said piston, said rod being connected with a slide valve adapted to operate with said port, a stop plate in said cylinder adapted to regulate the backward movement of said last named piston, a pipe leading from said last named cylinder at a point intermediate the normal position of said last named piston and said stop plate, 20 thence through a graduating valve to a tank, a pipe leading from said tank to said last named cylinder at a point intermediate said stop plate and said port, a port leading from said first named cylinder to the valve 25 seat of said valve, means for connecting said last named port to the atmosphere with said valve, means for conveying main air reservoir pressure to said valve, and means connecting said valve with the train line pipe, 30 as set forth.
11. In an air brake system a valve, means for connecting the valve with the main air reservoir pressure, means for automatically opening said valve with the exhaust from 35 brake cylinder through a triple valve, means for automatically closing said valve with said main reservoir pressure, a reduction
- cylinder connected with said valve, means connecting said cylinder to the train line pipe, means for taking an increased reduction 50 from the train line pipe to the rear of said cylinder by means of the reduction from the front train line pipe, and an automatic means for maintaining normal train line pipe pressure in said rear train line pipe, 55 as specified.
12. In an air brake system a reduction cylinder connected at an intermediate point in the train line pipe, means for supplying main air reservoir pressure to said cylinder, 60 a train line pressure governor consisting of a cylinder, the rear end thereof being connected to said first named cylinder, a pipe connecting the front of said last named cylinder to the main air reservoir, a piston in said 65 last named cylinder, a rod thereon, a spring on said rod bearing between the rear of said piston and the rear of said cylinder, a port leading from said last named cylinder intermediate the forward end of said piston and 70 said cylinder, and a valve secured to the piston rod and adapted to co-act with said last named port, as specified.
13. In an air brake system, means for automatically taking a reduction at an intermediate point in a train line, a means for automatically closing the throttle valve of an intermediate engine when said reduction is taken, said closing means consisting of a cylinder arranged near the throttle lever, a piston in said cylinder, a rod on said piston extending outward and secured to the throttle lever, means on said rod for releasing the escapement on said lever, a pipe leading from said cylinder to said reduction means, and 80 means for permitting air pressure to enter said pipe when a reduction is taken, as set forth.
- In testimony whereof I affix my signature in presence of two witnesses.
